US00D897832S

(12) **United States Design Patent** (10) **Patent No.:** **US D897,832 S**
(45) **Date of Patent:** **** Oct. 6, 2020**

(54) **SANDWICH WRAP CONTAINER**

(71) Applicant: **Inline Plastics Corp.**, Shelton, CT (US)

(72) Inventors: **Christopher John Pohlman**, West Haven, CT (US); **Victor Ivenitsky**, South Salem, NY (US)

(73) Assignee: **Inline Plastics Corp.**, Shelton, CT (US)

(**) Term: **15 Years**

(21) Appl. No.: **29/650,742**

(22) Filed: **Jun. 8, 2018**

(51) LOC (12) Cl. **09-03**

(52) U.S. Cl.

(74) *Attorney, Agent, or Firm* — McCarter & English, LLP; David J. Silvia, Esq.

(57) **CLAIM**

The ornamental design for a sandwich wrap container, as shown and described.

DESCRIPTION

FIG. 1 is a perspective view of the sandwich wrap container of the subject disclosure, shown closed;

FIG. 2 is a front elevation view of the sandwich wrap container of FIG. 1;

FIG. 3 is a rear elevation view of the sandwich wrap container of FIG. 1;

FIG. 4 is a right side elevation view of the sandwich wrap container of FIG. 1;

FIG. 5 is a left side elevation view of the sandwich wrap container of FIG. 1;

FIG. 6 is a top plan view of the sandwich wrap container of FIG. 1; and

FIG. 7 is a bottom plan view of the sandwich wrap container of FIG. 1;

FIG. 8 is a perspective view of the sandwich wrap container of FIG. 1, shown open and showing an interior design;

FIG. 9 is a rear elevation view of the sandwich wrap container of FIG. 8;

FIG. 10 is a front elevation view of the sandwich wrap container of FIG. 8;

FIG. 11 is a left side elevation view of the sandwich wrap container of FIG. 8;

FIG. 12 is a right side elevation view of the sandwich wrap container of FIG. 8;

FIG. 13 is a top plan view of the sandwich wrap container of FIG. 8; and,

FIG. 14 is a bottom plan view of the sandwich wrap container of FIG. 8.

The broken lines shown in the drawings do not form part of the claimed design.

1 Claim, 10 Drawing Sheets
